UNITED STATES PATENT OFFICE.

JOHN J. LE DUC, OF MANKATO, MINNESOTA.

INCUBATOR.

1,267,426.

Specification of Letters Patent. Patented May 28, 1918.

Application filed August 27, 1917. Serial No. 188,414.

To all whom it may concern:

Be it known that I, JOHN J. LE DUC, a citizen of the United States, residing at Mankato, in the county of Blue Earth and

5 State of Minnesota, have invented a new and useful Incubator, of which the following is a specification.

The present invention appertains to incubators, and aims to provide a hatching and 10 brooding machine which will, in a mechanical way, imitate nature's method of hatching eggs, to produce more healthy and perfect chicks, and to eliminate the many disadvantages and objectionable features of 15 prevailing types of incubators.

The main and primary object of the invention is the provision of an incubator (useful also as a brooder) provided with a hatcher supplied with heat by means of 20 heated fluid or other medium, and adapted to contact directly with the eggs, in the manner of nature, whereby to apply the proper temperature directly to the upper portions of the eggs, and thus closely imitate the natural 25 method of hatching.

Among the advantages of the present incubator over those now prevalent, may be mentioned the facts that the present construction eliminates the presence of cold corners, dispenses with the use of double walls, insulation, dead air spaces, etc., requires no extra nursery, has no egg tray or drawer to slide in and out which has proven objectionable, necessitates no moisture pan or humidifier, eliminates obnoxious gas fumes in the egg chamber, requires less heat and fuel than ordinary incubators, and effectively serves the purpose of a brooder after the eggs are hatched to comfort and quiet the chicks and 40 prevent the prostration thereof by overheating or the chilling thereof by a cold draft as when the doors of ordinary incubators are opened. Other advantages of the present incubator will appear as the construction 45 thereof is better understood.

The invention has for a further object, the provision of an incubator of the character indicated possessing novel features of construction, whereby to enhance the utility and 50 efficiency thereof.

With the foregoing and other objects in view, which will appear as the description proceeds, the invention resides in the combination and arrangement of parts and in 55 the details of construction hereinafter described and claimed, it being understood that

changes in the precise embodiment of the invention herein disclosed can be made within the scope of what is claimed without departing from the spirit of the invention. 60

The invention is illustrated in the accompanying drawings, wherein:

Figure 1 is an elevation of the incubator, portions being shown in section.

Fig. 2 is an elevation of the hatcher. 65

Fig. 3 is an elevation of the egg tray or pan, showing the curtain at one side thereof.

Fig. 4 is a bottom view of the hatcher with the diaphragm removed.

Fig. 5 is an enlarged sectional detail on 70 the line 5—5 of Fig. 1.

The incubator is conveniently supported by a single pedestal or standard 1 having a suitable foot or base 2 for attachment to the floor, and this pedestal provides a single leg, 75 making it easy to clean the floor around the incubator. The pedestal has an X-fitting 3 disposed therein between its ends, and has attached to its upper end a T-fitting 4. The upper end of the pedestal 1 is closed, and a 80 horizontal pipe or arm 5 is attached at one end to the fitting 4 and has attached to its free end a T-fitting 6 from which the hatcher 7 is suspended.

The hatcher 7 is of circular or other suitable form, and embodies a hood 8 of sheet metal or other suitable material and a lower diaphragm 9 of soft pliant rubber or equivalent material which has its marginal portion upturned and fitting the grooved portion of the depending flange or apron of the hood 8 and clamped tightly thereto by a ring or hoop 10, the ends of which are drawn toward one another by a bolt 11. In order to prevent the central portion of the diaphragm 9 from dropping too low, upstanding hangers 12 are vulcanized or otherwise attached to the diaphragm and have loops at their upper ends engaging a ring 13 between the diaphragm and top of the hood, and said ring 10 is in turn suspended from depending hangers 14 soldered or otherwise attached to the top of the hood. The hangers have loops or eyes loosely engaging the ring 13, whereby the diaphragm is free to yield while suspended by the hangers, in order that the diaphragm can lay snugly over the upper portions of the eggs to conform to the curvature thereof. The top of the hood 8 has a central upstanding thermostat housing 15 connected centrally by a nipple 16 with the fitting 6, and said housing incloses a suitable

105

110

thermostat 17 supported by a bridge bar 18 secured to the top of the hood and extending underneath the housing 15. The thermostat is used for accurately controlling the temperature, as hereinafter will more fully appear.

The top of the hood 8 has an outstanding neck 20 into which a cork 21 is fitted, and an ordinary thermometer 22 is slipped downwardly through the cork 21 so that its bulb is within the chamber of the hatcher, thus indicating the temperature of the fluid accurately and in a simple manner. The thermometer 22 can be protected by a guard 23 of any suitable construction mounted on the hood 8.

As illustrated, the hatcher is supplied with heated water as the heating medium, although any other suitable heated fluid or medium can be supplied to the hatcher. When the water circulating and heating plant is employed, there is provided an upstanding annular boiler 24 connected near its upper end by a nipple 25 with the fitting 4, so that the warm water flows through said fitting 4, pipe 5, fitting 6 and nipple 16 into the hatcher centrally thereof to flow radially in all directions over the diaphragm 9. The hood 8 is provided between its flange and top across the corner thereof with an inclined annular partition 19 having the apertures 19' near its lower edge, whereby the water which flows radially over the diaphragm 9 will flow practically uniformly in all directions to the apertures 19' and thence into the annular return space defined by the partition 19. The boiler 24 has an inlet nipple 26 near its lower end connected by a hose or flexible tubing 27, which extends through the fitting 3, to an elbow 28 attached to an outlet nipple 28' attached in turn to the flange of the hood 8 to communicate with the annular return space of the hatcher, for the return of the water from the hatcher through the hose 27 into the boiler, thus establishing the circuit for the siphon flow of the water, the hot water in the boiler rising to flow by way of the pipe 5 downwardly into the hatcher, and the cooler water at the periphery of the hatcher within the annular return space flowing downwardly through the hose 27 back into the boiler. The boiler is provided with an expansion tank 29 to keep the water circulating conduit full of water, and the boiler has a drain cock 29' near its lower end for emptying the boiler when desired.

The means for furnishing heat to the boiler include a flue 30 centrally within the boiler and spaced from the inner wall thereof, and an oil lamp 31 or other suitable heater disposed below the boiler. This lamp 31 is mounted on a standard 32 supported by a bracket 33 having a clamp 34 of any suitable construction embracing the

pedestal 1, and the bracket has a suitable clamp 35 embracing the standard 32. When the clamp 35 is loosened, the lamp 31 can be readily lowered for filling it with oil or other fuel, after which the lamp can be raised into position for properly heating the boiler.

The heating of the water is controlled by a damper 36 at the upper end of the flue 30 and carried by the lever 37 fulcrumed, as at 38, near the upper end of an upstanding pipe 39 attached to the fitting 6. A cap 40 is engaged upon the upper end of the pipe 39 and a rod or stem 41 is slidable through said cap, its upper end engaging the lever 37 and its lower end resting upon the thermostat 17. The movement of the damper 36 is, therefore, controlled by the thermostat, to thereby regulate the heating of the water to maintain a constant desired temperature in the hatcher. When the water cools slightly in passing into the hatcher, the contraction of the thermostat permits the rod 41 to move downwardly, thereby letting the damper 36 move downwardly to shut off the flow of the products of combustion from the lamp through the flue 30, and constraining said products of combustion to flow upwardly within the boiler in contact with its inner wall, thereby increasing the heat transmitted to the water, whereas when the temperature of the water rises adjacent to the incubator, the rod 41 in being moved upwardly, will raise the damper 36, and permit the products of combustion to flow outwardly through the flue 30, thereby removing some of the heat from the boiler, to lower the temperature of the water. In this manner the action of the thermostat serves to regulate the temperature of the water flowing into the hatcher to keep the temperature of the water constant on the diaphragm 9.

The eggs to be hatched are laid within an egg tray or pan having the bottom 42 of wood or other suitable material secured on the upstanding terminal of a bracket 43 provided at its basal end with a T-fitting 44 moving slidably upon the pedestal 1. This vertical sliding movement of the bracket 43 permits the egg tray to be raised and lowered. Said tray embodies the upstanding rim 45 of sheet metal or other suitable material attached to the periphery of the bottom 42 and of a size to snugly receive the hatcher 7, it being preferable to slightly flare the rim of the tray. The tray is provided at one side of its rim with a suitable door 46 which can be opened for inspecting the eggs or regulating the draft into the tray below the hatcher. The rim of the tray also has an upwardly opening slot 47 adjacent to the pedestal for receiving the outlet nipple 28' of the hatcher when the tray is raised. As a means for closing the slot 47 when the

tray is lowered, to prevent draft through said slot and to also prevent the chicks from sticking their heads through the slot 47 which might injure them, a pair of vertical rods 48 have their terminals secured to the tray at opposite sides of the slot 47, and coiled wire springs 49 are fitted on said rods, and have attached thereto a flexible curtain 50. When free to do so, the springs 49 in 10 recoiling will stretch the curtain 50 and move it upwardly over the slot 47, and when the tray is raised so that the nipple 28 moves into the slot 47, said nipple will move the upper edge of the curtain downwardly with 15 the springs 49, but as the tray is lowered, the springs will immediately move the curtain upwardly.

The downwardly movement of the tray is limited by a stop collar 51 secured adjustably 20 on the pedestal by means of a set screw 52 or the like, whereby the fitting 44 will rest on the collar when the tray is lowered with the bracket 43. The upward movement of the tray is limited by a nut 53 threaded 25 upon the pedestal 1 for adjustment. By adjusting the nut 53, the contact of the fitting 44 therewith will limit the upward movement of the tray, to bring the eggs properly 30 into contact with the diaphragm 9 to press upwardly into the under surface of the hatcher. When a lighter contact is desired, the nut 53 is screwed downwardly, especially 35 after hatching, when more space underneath the hatcher within the tray is desired.

An arcuate blade 54 is secured to the lower edge of the fitting 44 at that side thereof from which the bracket 43 projects, for holding the tray in raised position, it being 40 noted that when the tray is raised, the weight of the tray and bracket 43 will tend to swing them downwardly, thereby forcing the blade 54 tightly against the pedestal 1 to bite the same, and, therefore, bind the fitting 44 in place on the pedestal, and support the tray firmly in place. Then by raising the tray slightly, to relieve the pressure of the blade 54 against the pedestal, the tray 45 can be lowered.

50 A dash pot is provided for retarding the upward and downward movement of the tray, to avoid injury to the eggs. The pedestal 1 is hollow to provide a cylinder for the dash pot, in which a piston 55 slides. 55 The piston has an upstanding stem 56 within the pedestal provided at its upper end with a finger 57 projecting radially through a vertical slot 58 in the pedestal under the fitting 44. The stem 56 has a guide collar 59 near its upper end working within the pedestal, and a hook 60 is secured to the fitting 44 and engages under the finger 57, to move the stem 56 vertically with the fitting 44 and bracket 43. The pedestal or cylinder 1 is 60 provided at its lower end with a restricted

vent aperture 61 to provide for the restricted flow of air into and out of the pedestal as the piston 55 is raised and lowered, thus retarding the vertical movement of the tray and preventing it from being 70 dropped or raised with a jar.

In use, the eggs are readily placed in the tray when the tray is lowered, and when the tray is raised, the eggs are brought snugly against the diaphragm 9, the weight 75 of the tray causing the blade 54 to engage the pedestal 1 and hold the tray in place. The hot water circulates through the hatcher 7, flowing radially from the upper central inlet thereof over the diaphragm, thereby 80 heating the diaphragm and transmitting the heat directly to the upper portions of the eggs. Thus, by the pressure of the diaphragm 9 on the eggs and the direct transmission of the heat by contact with the eggs, 85 nature's method is closely imitated, for hatching the eggs in a most efficient manner. By this direct contact of the heating element, a lower temperature can be used than in ordinary incubators wherein the heat 90 must penetrate an air space to reach the eggs, thus effecting a saving in fuel with the use of the present arrangement. The eggs are heated uniformly, and should it be desired to turn them at intervals, the tray can 95 be lowered slightly for this purpose then returned into place. Attention can be given to the incubator while the operator is seated on the chair, including the replenishing of the oil in the lamp 31. After the hatching, 100 the door 46 can be opened to admit air under the hatcher, and the tray can be lowered slightly to comfortably accommodate the chicks therein under the hatcher. The diaphragm 9 in bearing on the backs of the 105 chicks will keep them warm and serve to comfort and quiet them. The thermostat is not subject to sudden changes in temperature, and the thermometer will accurately indicate the temperature and is not apt to 110 be disturbed as in ordinary incubators.

From the foregoing the advantages and attributes of the present incubator will be obvious without further description being necessary.

Having thus described the invention, what is claimed as new is:

1. An incubator including a hatcher having a flexible diaphragm, means for supplying heat to the upper surface of the diaphragm, and spaced means above the diaphragm for yieldingly supporting the central portion of the diaphragm, said supporting means including a ring connected to the top of the hatcher, and flexible hangers suspended from the ring and spaced apart, said hangers being connected at their lower ends to the diaphragm. 120

2. An incubator embodying a hatcher including a hood and a pliant diaphragm at- 125

tached to the flange thereof, the hood having a central inlet and outlet, means around its periphery, fluid circulating means connected to said inlet and outlet means, and 5 fluid heating means.

3. An incubator embodying a hatcher including a hood and a diaphragm attached to the flange thereof, fluid circulating means connected to the hood for the flow of fluid 10 therein over the diaphragm, and flexible means connecting the central portion of the diaphragm and hood for supporting the dia- phragm, including a ring between the dia- phragm and hood and hangers attached to 15 the diaphragm and hood and engaging said ring.

4. An incubator embodying a hatcher having a lower pliant diaphragm, means for supplying heat to the diaphragm from 20 above, and an egg tray below the hatcher, the hatcher and tray being movable verti- cally relatively, and the tray having an up- standing flared rim for snugly receiving the hatcher.

5. An incubator embodying a pedestal having an arm projecting to one side, a hatcher suspended from said arm and having a lower pliant diaphragm, means for supplying heat to said diaphragm, a bracket 30 movable vertically on the pedestal, and an egg tray carried by the bracket below the hatcher.

6. An incubator embodying a pedestal having an arm, a hatcher suspended from 35 said arm having a lower pliant diaphragm, means for supplying heat to said dia- phragm, a bracket slideable vertically on the pedestal, an egg tray carried by the bracket and having an upstanding flared rim to 40 snugly receive the hatcher, means for lim- iting the vertical movement of said bracket and for supporting it, and means for retard- ing the movement of the bracket.

7. An incubator embodying a hatcher, an 45 egg tray having an upstanding rim to re-

ceive the hatcher, fluid circulating means connected to the hatcher, the rim of the tray having a slot for receiving a portion of said means, and a spring pressed curtain carried by said tray and movable upwardly to close 50 the slot when the hatcher and tray are sepa- rated.

8. An incubator embodying a hatcher hav- 55 ing a lower pliant diaphragm, an inlet and an outlet member at one side, a vertically movable egg tray below the hatcher having an upstanding rim provided with a slot for receiving said outlet member, fluid circulat- ing means connected to the inlet and outlet members, and a spring pressed curtain car- 60 ried by the tray to move upwardly and close said slot when the outlet member is removed therefrom.

9. An incubator embodying a hollow hatching having a lower pliant diaphragm, 65 an egg tray below the hatcher, fluid supply- ing means connected centrally to the top of the hatcher, a thermostat centrally within the hatcher below said means, means for heating the fluid, and means controlling the 70 heating means operatively connected with the thermostat.

10. An incubator embodying a hatcher in- cluding a hood and a pliant diaphragm se- 75 cured to the flange thereof, an egg tray be- low the hatcher, fluid supplying means con- nected centrally to the top of the hatcher, a heater for the fluid, means for controlling the heating of the fluid, and a thermostat 80 centrally within the hood below the top thereof controlling the last mentioned means.

In testimony that I claim the foregoing as my own I have hereto affixed my signature in the presence of two witnesses.

JOHN J. LE DUC.
